UNITED STATES PATENT OFFICE.

JAMES REAGIN, OF BLOOMFIELD, IOWA.

RAILWAY.

1,013,441.

Specification of Letters Patent.

Patented Jan. 2, 1912.

Application filed May 1, 1911. Serial No. 624,483.

To all whom it may concern:

Be it known that I, JAMES REAGIN, a citizen of the United States of America, and resident of Bloomfield, Davis county, Iowa, 5 have invented a new and useful Improvement in Railways, of which the following is a specification.

The object of my invention is to provide an improved construction for railways, 10 which construction is peculiarly applicable to rails, means for preventing spreading of rails, and means for securing the rails to suitable supports or beds.

A further object of my invention is to 15 provide improved means for adjusting rails relative to each other in respect of gage and parallelism.

A further object of my invention is to provide an improved construction for a rail- 20 way rail.

A further object of my invention is to provide an improved construction of means for securing a railway rail to a bed or support.

25 My invention consists in the construction, arrangement and combination of elements hereinafter set forth, pointed out in my claims and illustrated by the accompanying drawing, in which—

30 Figure 1 is a plan, partly in section, of a portion of a railway embodying my improvements. Fig. 2 is a vertical section on the indicated line 2—2 of Fig. 1. Fig. 3 is a side elevation illustrating a joint in a 35 railway track and embodying my improvements. Fig. 4 is a vertical section illustrating a modified form of one part of my improved device.

In the construction of the railway as 40 shown the numeral 10 designates a bed or support which may be of any suitable material such as concrete, wood, metal, or a combination of any or all of such materials. Bed plates 11 are mounted on the bed or 45 support 10 and are formed with spaced holes registering with spaced holes in the bed. Upturned flanges 12 are formed on the inner ends of the bed plates 11 and are formed with bolt holes adapted to receive a strain- 50 ing bolt 13 or tie-rod, which straining bolt or tie-rod is threaded on both ends and is adapted to receive nuts 14 bearing on the outer faces of said flanges. It is the function of the straining bolt 13 to limit, de- 55 termine and prevent spreading apart of the bed plates 11 and to relieve spreading strain

from the bed and fastening means herein-
after described. Rails 15 are mounted on
the bed plates 11 and preferably centrally
of the spaces between the holes in said bed 60
plates. U-bolts 16 are mounted in the bed
10 and have their threaded end portions ex-
tending through the holes in the bed plates
on opposite sides of the rails 15. Wear
plates 17 are mounted above and in contact 65
with the closed end portions of the U-bolts
16 and are embedded in or contact with the
bottom of the bed 10. It is the function of
the bed plates 11 to prevent the rails 15
cutting or sinking into or breaking the bed 70
10 and it is the function of the wear plates
17 to prevent the U-bolts 16 from cutting
or sinking into or breaking said bed. The
base flanges of the rails 15 preferably are
formed convex in cross-section on their up- 75
per surfaces. Clamping plates 18 are
formed with concavo-convex marginal por-
tions 18^a adapted to overlie and fit the con-
vex upper surfaces of the base plates of
the rails, inner margins of said clamping 80
plates being adapted to contact with the
webs of the rails at lines of juncture of said
webs with the base flanges. The clamping
plates 18 also are formed with slots 19 adapt-
ed to receive the threaded end portions of the 85
U-bolts 16. The clamping plates 18 engage
at their lower outer edges with the upper
surfaces of the bed plates 11 adjacent the ends
of said bed plates and are inclined slightly
from the lines of engagement with said bed 90
plates to and over the base flanges of the
rails. Washers 20 are mounted on the
threaded end portions of the U-bolts 16 and
rest on the upper surfaces of the clamping
plates 18, said washers preferably being 95
wedge-shaped so that the lower surfaces
thereof conform to the inclination of the
clamping plates while the upper surfaces
thereof form right angles with the arms of
the U-bolts. Nuts 21 are screwed on the 100
threaded end portions of the U-bolts 16 and
engage the upper surfaces of the washers
20; and in use said nuts are set firmly, rig-
idly and accidentally-immovably on said
washers so as to bind the clamping plates 105
to the bed plates and effectually and firmly
connect the clamping plates, bed plates, bed,
wear plates and U-bolts. In such positions
the clamping plates 18 serve as levers hav-
ing their fulcrums at the edges contacting 110
with the bed plates, the power being ap-
plied by the nuts 21 and the load being rep-

resented by the force with which the concavo-convex marginal portions 18^a of said plates engage with and hold down the base flanges of the rails.

5 In practical use, as many of the clamping plates, U-bolts, wear plates, washers, nuts and bed plates may be employed as is desired and they may be arranged at any desired intervals throughout the lengths of
10 the rails.

15 In Fig. 3 I have shown how my improved device may be employed to support meeting ends of rails and at the same time permit longitudinal expansion and contraction of the rails under changes of temperature. The gage of the rails may be adjusted by
20 loosening the clamping effect of the plates 18 through the medium of the nuts 21 and after the gage is adjusted the rails may be fixed by tightening said clamping plates to the plates through resetting of said nuts. The bed plates 11 have sufficient area to prevent the jar and pounding of the rail from cutting into the bed, whether said
25 bed be of concrete, wood or metal, and loosening the support; and the wear plates have sufficient area to prevent the U-bolts from cutting into said bed at their closed ends.

30 In Fig. 4 I have shown the bed plates 11 without the flanges, thus adapting them for use without the straining bolts when it is not desired to connect side portions of the track to prevent spreading auxiliary to the connection afforded by the bed 10.

35 I claim as my invention—

1. An improvement in railways, comprising a bed, U-bolts mounted in said bed, end portions of said U-bolts extending above said bed, bed plates on said bed, rails on said bed plates, clamping plates engaging said bed plates and overlying the base flanges of the rails, said clamping plates formed with concavo-convex marginal portions fitted to base flanges of the rails, threaded end
40 portions of the U-bolts extending through said bed plates and clamping plates, and nuts on said end portions of the U-bolts.
45

2. An improvement in railways, comprising a bed, U-bolts mounted in said bed, end portions of said U-bolts extending above said bed, bed plates on said bed, rails on said bed plates, clamping plates engaging

said bed plates and overlying the base flanges of the rails, said clamping plates formed with concavo-convex marginal portions fitted to the base flanges of the rails, said clamping plates arranged in inclined positions relative to the bed plates, threaded end portions of the U-bolts extending through said bed plates and clamping plates, and nuts on said end portions of the U-bolts.
55
60

3. An improvement in railways, comprising a rail having its base flanges formed with convex upper surfaces, clamping plates formed with concavo-convex marginal portions adapted to engage and fit to said convex surfaces of the base flanges, and means for binding said clamping plates to a bed.
65

4. An improvement in railways, comprising a bed, U-bolts mounted in said bed, end portions of said U-bolts extending above said bed, bed plates on said bed, rails on said bed plates, clamping plates engaging said bed plates and overlying the base flanges of the rails, said clamping plates formed with concavo-convex marginal portions fitted to the base flanges of the rails, threaded end portions of the U-bolts extending through said bed plates and clamping plates, nuts on said end portions of the U-bolts, and a straining bolt connecting said bed plates.
70
75
80

5. An improvement in railways, comprising a bed, U-bolts mounted in said bed, end portions of said U-bolts extending above said bed, bed plates on said bed, rails on said bed plates, clamping plates engaging said bed plates and overlying the base flanges of the rails, said clamping plates formed with concavo-convex marginal portions fitted to base flanges of the rails, threaded end portions of the U-bolts extending through said bed plates and clamping plates, nuts on said end portions of the U-bolts, said bed plates formed with upturned flanges at their adjacent ends, and a straining bolt connecting said upturned flanges.
